(57) **CLAIM**

The ornamental design for an electric kettle, as shown and described.

DESCRIPTION

FIG. 1 is a top and rear perspective view of an electric kettle showing my new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a rear elevational view thereof; and,

FIG. 6 is a top plan view thereof.

Material shown in broken lines is not claimed.

The bottom of the electric kettle is not seen in use and its appearance is not claimed.
